UNITED STATES PATENT OFFICE.

WILLIAM W. MECHLING, OF BUTLER, PENNSYLVANIA.

METAL RAILROAD TIE.

Application filed December 29, 1926. Serial No. 156,371.

My invention is an improvement in metal railroad ties and relates to that particular form in which the tie is constructed of a metal bar or rail bent upon itself at its ends to provide anchorage for the tie in the road bed and bearings for the rails supported on said ends, in some instances wooden blocks being secured in the bent ends of the tie to receive the rails and absorb the shock of the traffic moving thereover.

In the present instance my invention contemplates an arrangement by which metal ties of this general type are employed and connected to each other at their ends in a particular manner whereby a track construction is provided that is not only strong and durable but is not liable to get out of alignment or shifted thus permitting my improved construction to be used for heavy traffic and for fast moving trains.

My invention further contemplates the employment of bars or rails of different shapes in cross-section to meet requirements of traffic, for instance angle-bars and channel-bars for heavy traffic and T-bars or ordinary railroad rails for lighter traffic, in each instance the metal ties forming the supports for the rails being firmly connected to each other at their ends and preferably provided with wooden blocks to give the required resilience to the rails.

With these principal objects in view my invention consists in the particular construction and arrangement of parts employed in the construction of the railroad track, all as hereinafter fully described and specifically set forth in the appended claims.

In the accompanying drawings:

Figure 1 is a plan view of a railroad track constructed in accordance with my invention.

Figs. 2, 3 and 4 are sectional views on the lines 2—2, 3—3 and 4—4 of Fig. 1.

Figs. 5 and 6 are detail views of the metal clamp for connecting the terminals of adjoining ties.

Figs. 7 and 8 are plan views showing modifications in the form of metal tie that may be used.

Fig. 9 is a sectional view on the line 9—9 of Fig. 7, and

Fig. 10 is a sectional view on the line 10—10 of Fig. 8.

Like numerals of reference are used to indicate like parts in the several views of the drawings.

In the embodiment of my invention as illustrated on Sheet 1 of the drawings angle-bars 15 are employed in the construction of the track, the ends of each angle-bar being bent towards each other at one side of the body portion to provide curved ends or loops 16 with the vertical flange 15^a of the angle-bar at the inner side of the loops and the horizontal flange 15^b forming the base of the tie, it being understood that said end loops are of sufficient length and width to provide the required anchorage as well as to give ample support for the rails 17. These metal ties are used in connection with wooden blocks 18 and 23 forming resilient seats for the rails, and to receive said blocks in the construction of a railroad track the metal ties are arranged in pairs as shown in Fig. 1, that is to say with the base flanges 15^b of the body portions of the two ties extending towards each other and the curved ends or loops 16 extending in opposite directions from said adjoining body portions, the blocks 18 being located at the ends of the body portions between the opposite loops while the blocks 23 are located between the terminals of adjoining ties, as hereinbefore explained. The wooden blocks extend above the plane of the metal ties so that the rails will not come in contact with the latter, and although the rails may be supported directly on said blocks I prefer to use interposed metal plates 20 through which the rail-spikes 21 and plain spikes 22 are driven into the block. As hereinbefore stated the wooden blocks 18 are near the ends of the body portions of two adjoining metal ties, being secured in place by bolts 19, and it will be understood that the width of these blocks will determine the spacing of the metal ties from each other, the base flanges 15^a 15^b supporting them and the bolts locking the companion ties together. The pair of ties so connected is bolted to a similarly connected pair of ties by the blocks 23 interposed between the terminals of adjoining loops or curved ends 16 and secured by bolts 19, but in order to reinforce the bolts and thereby more effectively prevent longitudinal displacement of the ties or shifting of the track laterally metal clamps 24 are used in connecting the curved ends of adjoining ties together, said clamps embracing the blocks 23 with their ends 24^a bent around the upstanding flanges of the ties at the ends thereof, the bolts passing through the con-

nected parts as shown in the drawings. Plates 20 are also placed on these blocks for the rails to rest upon.

It will be readily seen that a railroad track constructed in the manner hereinbefore described, with each pair of curved end ties firmly connected together and to adjoining pairs of ties the rails will be firmly supported on the roadbed against longitudinal creeping or lateral displacement inasmuch as the ties being all connected together will serve to reinforce one another to provide a strong and durable track construction for heavy traffic and fast moving trains.

16 My invention also contemplates the use of angle bars in the form of T-bars 27, shown in Fig. 11 of the drawings, the ends being bent towards each other at one side of the body portion to provide the curved ends or loops 28, and in constructing a railroad track two of these metal ties would be placed side by side in the same manner as the angle-bars 15 and blocks, as 18, placed between the upstanding flanges 27^a to rest on the inner base flanges 27^b. The railroad rail used in the construction of the tie shown in Fig. 12 is practically a T-bar, being similarly bent at its ends to provide the curved ends or loops 30 and having the upstanding flange 29^a and base flanges 29^b. Obviously therefore bars or rails of various forms in cross-section may be used in the construction of a railroad track in accordance with my invention, and consequently I do not limit my

protection to any particular cross-sectional shape of bar or rail within the spirit and scope of my claims, the term angle bars being intended to include double angle bars or T-rails.

I claim:

1. A metal railroad tie comprising a pair of angle-bars arranged side by side and having end portions bent in opposite directions, and means connecting the angle-bars together to form the tie. 40

2. A metal railroad tie comprising a pair of angle bars arranged side by side with the base flanges extending towards each other and having end portions bent in opposite directions for connecting the ties together continuously in the construction of the track, and wooden blocks connecting the angle-bars and seated on adjoining base flanges thereof. 45

3. A metal railroad tie comprising a pair of angle-bars arranged side by side with base flanges extending towards each other and having end portions bent in opposite directions for connecting the ties together continuously in the construction of the track, blocks for supporting the rails bolted on the adjoining base flanges at the ends of the body portions of the associated angle-bars, blocks bolted on the adjoining base flanges of the ends of adjoining ties, and metal clamps embracing the last mentioned blocks 55 and bent around the ends of the ties. 60
